UNITED STATES PATENT OFFICE.

DOMENIC M. CAMPANA, OF CHICAGO, ILLINOIS.

CHINA-KILN ATTACHMENT.

1,275,383.

Specification of Letters Patent. Patented Aug. 13, 1918.

Application filed October 29, 1917. Serial No. 199,215.

To all whom it may concern:

Be it known that I, DOMENIC M. CAMPANA, a citizen of the United States, residing at Chicago, in the county of Cook and 5 State of Illinois, have invented certain new and useful Improvements in China-Kiln Attachments, of which the following is a specification.

My invention relates to china kiln attachments, and has for one of its objects the provision of a simple and efficient attachment for inserting in china kilns, and the like, to provide even temperatures in the part of the interior of the kiln, or the like, 15 inside of the attachment.

A further object is the provision of an attachment, such as mentioned, which can be easily and quickly fitted in and taken out of a china kiln, or the like, and one which 20 can be easily and quickly taken apart and put together.

Other objects will appear hereinafter.

An embodiment of my invention is shown in the accompanying drawing, forming a 25 part of this specification, and in which—

Figure 1 is a front view of a conventional china kiln with its door open and fitted with an attachment embodying my invention.

Fig. 2 is a side view of an embodiment 30 of my attachment with a portion broken away to show parts of the interior; and

Fig. 3 is an enlarged section taken on line 3—3 of Fig. 2.

In china kilns of conventional construction there are higher temperatures at the lower portion of the kiln than the upper due to the source of heat being situated in the bottom of the kiln. Also the interior of the kiln sometimes has drafts and other 40 unevenly heated portions therein. These uneven temperatures in the kiln make it difficult to fire substances, such as glassware, which have tendencies to become soft, lose their shape and collapse when heated 45 too strongly at their base or at one special side. My attachment is to provide an even temperature, top, bottom and at the sides, making the firing of glassware or the like more perfect and correct.

50 Referring more particularly to the drawing, I have indicated a china kiln 5, which may be of any conventional or preferred form, having a door 6, which is usual with such kilns. My attachment comprises a 55 housing or walls which have comparatively high heat conducting qualities and which

are adapted to entirely inclose a portion of the interior of the kiln. As an example of such a housing, I have shown a sheet metal housing comprising an upper portion 7 and a lower portion 8. The portion 7 includes the top and upper halves of the side walls of my attachment, and the lower half 8 includes the lower portions of the side walls and the bottom of my attachment. The part 7 is provided with the upper portion 9 of a rear wall, and the portion 8 is provided with the lower portion 10 of the rear end wall. When these parts are together, as indicated in Fig. 1, the sides 70 of the housing are all closed, except the front side. This front side is adapted, when the attachment is in a kiln, to be very close to and substantially closed by the door 6 of the kiln, so that there is very little or 75 no circulation of the air in the kiln from the outside of the attachment to the inside thereof. This arrangement provides means whereby the interior of the attachment is heated by the heat passing through the walls 80 of the housing thereof. With this arrangement the temperature of the interior of the housing is substantially uniform throughout. Therefore, glassware, or other similar objects, can be placed in the upper and lower 85 portions of this attachment without danger of injuring any of them. In placing glassware, and the like, in the ordinary kilns, owing to the strong heat at the bottom and at the farther part of the kiln back from the 90 door, a quantity of glass pieces will collapse, while other glasses placed on shelves nearer the door or toward the upper part of the kiln, will be fired correctly or even not fired enough to properly carry out the color 95 decorations.

The housing shown is provided with flanges 11 and 12 on the portions 7 and 8, respectively, with registering perforations 13 in said flanges. In the perforations 13 100 are provided pins 14. It will be seen from this construction that the upper part of the housing can be lifted directly off the lower portion when not in a kiln to separate the parts, or the pins 14 may be removed from 105 the perforations, and the parts separated. This illustrates an easy means for connecting the upper and lower parts of the housing. At the rear of the housing on the portions 9 and 10, I provide flanges 15, or any 110 other suitable extensions to engage the back wall 16 of the kiln in order to hold the open

side of the housing in close proximity to the door 6 of the kiln when the latter is closed. The flanges 11 and 12 also have the function of holding the attachment in substantially the center of the kiln and preventing the sides of the attachment from engaging the sides of the kiln, thereby insuring an air space between the sides of the kiln and my attachment at all times.

10 In the attachment I preferably provide a plurality of shelves so that a number of articles, such as indicated at 17 in Fig. 1, may be accommodated at one time. These shelves are preferably supported by ledges 18 on the inner walls of the housing.

15 The lateral edges of at least the shelf nearest the middle of the housing are preferably in close proximity to the inner walls of the housing. Hook members 19 are 20 formed on certain of the ledges 18, adjacent the open side of the housing, which engage hook members 20 on one of the shelves 21. This arrangement provides means whereby the sides of the housing, adjacent the 25 opening in the latter, are held against lateral movements both toward and away from each other.

20 The top and bottom of the housing are preferably semi-cylindrical or curved upwardly and downwardly, respectively, in order to prevent forming sharp corners on the interior of the attachment, and to provide means so that the heat in the interior 30 of the kiln outside of the housing can easily 35 pass up around the attachment. In order to hold the bottom of the attachment above the bottom of the kiln, I have provided legs 22, which may be secured to the lower portion 40 of the housing in any desirable manner, such as by rivets 23.

45 While I have illustrated and described the preferred form of my invention, I do not desire to be limited to the precise details set forth, but desire to avail myself of such variations and changes as come within the scope of the appended claims.

I claim:

1. In combination, a china kiln having a door at one side thereof; a housing in the

50 kiln having an opening in its side adjacent the door; and an extension on the housing intermediate the top and bottom of the latter adapted to engage the inner wall of the kiln opposite the door and hold the housing in a position with its open side substantially 55 against the door of the kiln to close said opening.

2. In combination, a china kiln having a door at one side thereof; a sheet metal housing in the china kiln having its side adjacent 60 the door of said kiln open; and a substantially horizontal outwardly extending flange on each of the closed sides of the housing intermediate the top and bottom of the latter facilitating the positioning of the housing 65 in said kiln and holding the open side of said housing close to the door of the kiln.

3. An attachment for china kilns comprising a housing made up of a top, a bottom, side walls and one end wall with the other 70 end of the housing open and said end and side walls being divided on a substantially horizontal plane; means loosely connecting the portions of said end and side walls together; ledges on the side walls along the 75 division of the latter; hook members on the ledges adjacent the open end of said housing; and a shelf on said ledges having hooked portions thereon engaging said hook members and holding the side walls against 80 spreading.

4. An attachment for china kilns comprising a sheet metal housing having one side open and made up of upper and lower portions; means holding the engaging edges of 85 the upper and lower portions against relative lateral displacement; ledges on the inner walls of one of said portions extending along the adjacent edges of said portions and terminating close to the open side of 90 the housing; hook members on the ledges at the open side of the housing; and a shelf resting on the ledges and having parts engaging said hook members.

95 In testimony whereof I have signed my name to this specification on this 24th day of October A. D. 1917.

DOMENIC M. CAMPANA.
